CLAIM

The ornamental design for ski-sled, as shown and described.

DESCRIPTION

FIG. 1 is a perspective view of a ski-sled embodying my new design;

FIG. 2 is a rear elevation of the ski-sled shown in FIG. 1;

FIG. 3 is a side elevation of the ski-sled shown in FIG. 1;

FIG. 4 is a front elevation of the ski-sled shown in FIG. 1;

FIG. 5 is a top plan view of the ski-sled as shown in FIG. 1; and,

FIG. 6 is a bottom plan view of the ski-sled as shown in FIG. 1.

The broken lines in FIGS. 1 through 6 are for illustrative purposes only and form no part of the claimed design.

FIG. 1

FIG. 5

FIG. 6

FIG. 4
